UNITED STATES PATENT OFFICE.

EDWARD FRASER, OF NORTH CRANDON, WISCONSIN.

RAIL-JOINT.

No. 914,260.

Specification of Letters Patent. Patented March 2, 1909.

Application filed June 5, 1908. Serial No. 436,953.

To all whom it may concern:

Be it known that I, EDWARD FRASER, a citizen of the United States, residing at North Crandon, in the county of Forest and State of Wisconsin, have invented new and useful Improvements in Rail-Joints, of which the following is a specification.

This invention relates to rail joints of the scarf type, the object of the invention being 10 to provide a rail joint which will insure a smooth surface for cars passing over the same and avoid the liability of forming flat places adjacent the joints, and also overcoming to a great extent the liability of the 15 rails to spread adjacent to the joints. The construction hereinafter described also dispenses with the usual angle bars or fish plates now in common use and provides means whereby the joint will brace itself 20 even should the usual clamping bolts get out of place.

With the above and other objects in view, the nature of which will more fully appear as 25 the description proceeds, the invention consists in the novel construction, combination and arrangement of parts as herein fully described, illustrated and claimed.

In the accompanying drawing:—Figure 1 is a side elevation of a rail embodying the 30 present invention. Fig. 2 is a plan view of the same. Fig. 3 is a vertical longitudinal section through the joint. Fig. 4 is an enlarged detail perspective view of the splice bar. Fig. 5 is a perspective view of one end 35 of one of the rails.

Referring to the drawings, 1 and 2 designate the rail ends, one of which is illustrated in detail in Fig. 5 and both of which are formed in the manner shown in Fig. 5.

40 Adjacent to the end of each rail, the latter is formed with a comparatively thick or solid portion 3 beneath which the base flange 4 of the rail is cut away from the joint 5 to the extremity of the rail as clearly shown in Fig.

45 5 so as to admit the base flange of the splice bar shown in Fig. 4 and hereinafter more particularly described.

In addition to cutting away the base flange 4 of the rail, the body and head of the 50 rail are cut away as shown at 6 to provide a longitudinally extending tongue 7 of about one-half the thickness of the thickened body portion of the rail and the said tongue is notched or cut away to leave a projecting 55 tenon 9 which extends beyond the extrem-

ity of the tongue 7 and forms a continuation of the head of the rail as clearly illustrated in Fig. 5.

Both of the rail ends are formed in the manner hereinabove just described, and they 60 are connected by means of a splice bar 10 shown in detail in Fig. 4, wherein it is seen to comprise a base flange 11, a cheek plate 12 extending longitudinally along the same adjacent to one side edge thereof, a rail head 65 section 13, which also extends lengthwise of the base flange 11 but terminates short of the ends thereof, and an abutment 14 which extends from the cheek plate 12 to the rail head section 13 and provides horizontal and 70 vertical shoulders against which the extremities of the rail abut in the manner clearly shown in Figs. 2 and 3.

In assembling the parts, the tongue 7 of 75 each rail end is inserted between the cheek plate 12 and the rail head section 13 at one end of the splice bar, the tongue 7 filling said space and the end shoulder thereof resting against one of the vertical shoulders of the 80 abutment 14 while the lower surface of the projecting tenon 9 rests upon one-half of the horizontal shoulder of the abutment 14 as clearly seen in Fig. 3. When the two rail ends are brought into proper relation with the splice bar as shown in Figs. 2 and 3, the 85 extremities of the tenons 9 abut or lie closely together as shown and these bolts 16 and 15 are inserted through the overlapping parts of the joint including the projecting tongues 7 and the oppositely lying portions 90 12 and rail head section 13 thereby forming a secure connection between the rail ends and the splice bar. Even should the bolts 15 and 16 become displaced, the splice bar 95 would form a sufficient brace between the ends of the rail so as to prevent the breaking away or splitting of the rails adjacent to the joint.

I claim:—

In a rail joint, the combination of rail ends 100 having the base flanges thereof cut away from the extremity of the rail, and also having the body portions of the rails cut away at one side to leave longitudinally projecting tongues which are in turn notched or cut 105 away to leave tenon extensions beyond the extremities of the tongues, and a splice bar comprising a base flange, a cheek plate extending along one side thereof, a rail head section extending lengthwise of the base 110

flange parallel to the cheek plate, and an abutment connecting the cheek plate and rail head section and providing vertical and horizontal shoulders against which the corresponding shoulders on the projecting tongues and tenons of the rail ends rest, substantially as described.

In testimony whereof I affix my signature in presence of two witnesses.

EDWARD FRASER.
